UNITED STATES PATENT OFFICE.

ADALBERT DOMARADZKI, OF CLEVELAND, OHIO.

FLYING-MACHINE.

1,098,024.

Specification of Letters Patent.

Patented May 26, 1914.

Application filed June 24, 1913. Serial No. 775,522.

To all whom it may concern:

Be it known that I, ADALBERT DOMARADZKI, citizen of the United States, residing at Cleveland, in the county of Cuyahoga and State of Ohio, have invented certain new and useful Improvements in Flying-Machines, of which the following is a specification.

This invention relates to flying machines of the heavier than air type and embodies a car, and means to elevate and propel the same, the elevating means consisting of upper and lower sets of wings, and horizontal propellers, that is, propellers rotating on a vertical axis. These propellers drive currents of air downwardly, and by means of chutes or guides these currents of air are directed under the wings. The propelling means comprise screw propellers of ordinary type arranged vertically, that is rotating on horizontal axes. Suitable steering devices are also provided. The wings are of special construction, and when not in use for elevating the machine, may be held in fixed position to act as planes.

The invention is illustrated in the accompanying drawings in which—

Figure 1 is an end view of the machine. Fig. 2 is a side view of the body of the car. Fig. 3 is a top plan view showing the upper wing on one side and a lower wing on the other side. Fig. 4 is a top plan view with the wings removed. Fig. 5 is a detail of the operating devices for the lower wings. Fig. 6 is a detail of one of the air chutes. Fig. 7 is a detail transverse elevation, partly in section, of the operating devices for the wings. Fig. 8 is a perspective view of the operating connections for the wings. Figs. 9 and 10 are details.

Referring specifically to the drawings, 6 indicates the car body, which may be made of any suitable size and shape and serves to carry the operators and the motors, and such other devices as may be appropriate. This body is provided with wheels 70 so that it will run on the land. Mounted upon the framework of the body are upper and lower frames 28 connected by supports 28^a, and the wings work in these frames. The upper wings are indicated at A, the lower wings at B, the former being made in two

sections with a longitudinal hinged joint at 27 so that they will flex when lifted as shown in dotted lines in Fig. 1.

80 is an engine which drives a belt 7 and a pulley 8, the shaft 8^a of which is carried in suitable bearings in the car, and said shaft also carries a cam wheel 9 which works in a cross head frame 10 which slides up and down in guides 10^a at opposite ends thereof. Connected to the frame 11 by pivots 11^b are links 11, and the upper ends of these links are fastened to levers 11^a by pivots 11^c. The outer ends of the levers 11^a are pivoted at 11^d to links 12^a, the lower ends of which are pivoted at 12^e to levers 12^b, and pins at the upper ends of the links 12^a slide in slots 12^c in fixed bars 13^a on the frame. The levers 12^b are pivoted at 12^d to the frame at one end, and at the other end are pivoted at 13^b to links 13^c the upper ends of which are pivoted to levers 13^d which are pivoted at one end, at 13^e, to the frame, and connected at the other end to a vertically movable bar 13 which is the main operating bar for the wings. The inner ends of the levers 11^a are provided with pins sliding in slots 12^e in the frame portions 12. When the cross head 11 moves up and down the links 11 swing the levers 11^a, 12^a, 12^b, and 13^c, thereby reciprocating the standard 13. The slots 12^c and 12^e permit a certain amount of lost motion and are designed to prevent jar. By means of these slots the links and levers travel until the pins in the slots reach the ends thereof, giving a periodical motion to the wings. The bar 13 has a pin 14 and slot 14^a connection to levers 15 which are pivoted at 16 to the car body, at one end, and at the other end are connected by links 17 to bars 18 which slide up and down in guides at the ends of the car body. Connected to the bars 18, by the pin and slot connections at 190, are cross levers 19^a pivoted at one end at 191 to the frame of the car body and at the other end to links 24 pivotally connected to sectional levers 24^a which are fulcrumed at 240 to the uprights 241 constituting part of the frame and which are connected at their outer ends to the upper wings A by means of pivoted links 25. These wings are hinged in the frame 28 at 26, and a closed plane or part 280 extends

between the wings at the top. One section of each lever 24 works between branches 250 and 251 of an arcuate guide attached to the other section.

- 5 The lower wings B are pivoted at 23 to the frame of the machine and are comparatively short. To operate these, cross levers 20 are connected at their inner ends to the vertically sliding bar 13, by links 200, and 10 are fulcrumed at their outer ends on brackets 20^a mounted on the uprights 242 of the car. The levers 20 are pivotally connected to bars 21 which are connected to blocks 22 sliding in guides 220 (Fig. 5) and these 15 blocks are connected to a chain or arrangement of rigid links 248, flexibly connected or pivoted to each other which work on a quadrant 209 connected to each wing B, whereby the reciprocation of the blocks 22 20 flaps the wings B up and down.

When the upper wings are not in use they are held in fixed position by means of hooks 29 engaging pins on said wings, these hooks being operated by the cords 30, extending into the car, and these cords are 25 also connected to a curtain or sliding cover 31 which may be drawn to cover the joint between the end of each wing and the outer part of the frame 28 to make the device as 30 nearly air tight as possible so that it can then be used as a plane in gliding or direct traveling. The lower plane 28 is provided with a curtain 31^a which may be drawn by a cord 30^a to close the space between the 35 outer part of the lower frame 28 and the end of each lower wing B, to form a plane, or when the wings are operating, the curtains 31^a may be drawn up or folded, as shown in Fig. 1, to allow the tipping of the upper 40 wing A to swing down into the space beyond the outer end of the lower wing B, as shown in dotted lines in Fig. 1. The cords 30^a also operate panels 32, by means of links 33, to open or close said panels by lateral movement. The panels are opened when the upper wing is operating, and are closed when the wings are fixed, in order to form a lower 45 plane, in connection with the lower frame 28 and the wing B, the panels fitting between the front and rear ends of the wing 50 and the adjacent parts of the frame 28.

The lifting propellers are indicated at 39. There is a pair of these at each end of the car. They are driven by means of an engine 55 60 which drives a belt 61 which in turn drives a longitudinal shaft 40, geared to upright shafts 400 which by appropriate belt and sprocket gearing indicated at 401 and 402 drives said propellers 39. These propellers are located at the upper ends of chutes 34 which curve downwardly and inwardly to direct the air under the wings B, thereby increasing the resistance to said wings and assisting the lifting power. The 60 65 chutes 34 comprise a framework of ribs 36,

a fabric cover 35, the upper ends of the ribs having balls 37 which slide in frames 38 whereby, when desired, the chutes may be folded or collapsed by pushing the ribs around to one end of the frame 38.

70 The vertical propellers are indicated at 41, and they are driven by belts 500 from the shaft 40. Four of these propellers are used, two at each end, as indicated in dotted lines in Fig. 1. These serve the purpose of driving the car forwardly.

75 The lifting power is supplied by the flapping wings A and B and the lifting propellers 39, and the driving power by the propellers 41. When the car is at sufficient height the wings A and B may be held fast to act as planes, in connection with the covered frames 28.

80 42 are rudders which are operated by means of a lever 43 pivoted at 43^a in the car and turned by a shaft 44 operated by any suitable steering device such as a steering wheel 600.

85 45 is a rear plane or rudder which may be 90 swung up or down by means of a lever 46 and a wire 45 connected to a lever 800 which is connected to a bar projecting from the rudder.

95 The details of the connections are largely diagrammatic in the illustration and may be varied or provided by mechanical skill.

I claim:

1. In a flying machine, the combination of a car, upper and lower frames mounted thereon, and forming planes, upper and lower sets of wings working in openings in said frames, means to hold the wings in fixed position when desired, in said openings, to form planes in connection with said frames, and means to propel the machine.

100 2. In a flying machine, in combination, a car, upper and lower frames mounted thereon and provided with plane sections, upper and lower sets of wings mounted in openings in said frames to form planes in connection therewith, means to close the openings between the edges of the wings and the frames, and means to propel the car.

105 3. In a flying machine, the combination of a car, collapsible chutes at opposite ends thereof, flapping wings at opposite sides of the car and lifting propellers at the upper ends of the chutes, said chutes being shaped to direct currents of air downwardly from said propellers to the space under the wings.

110 4. In a flying machine, the combination of a car, planes at opposite sides thereof, flapping wings working in openings in said planes, and screw propellers at opposite ends of the car, and chutes arranged to direct currents of air from said propellers to the space under the planes.

115 5. In a flying machine, the combination of a car, an upper plane thereon provided with openings, flapping wings working in

said openings at opposite sides of the car, lower planes provided with openings, lower wings working in the openings in the lower planes and curtains operable to close the 5 openings in the lower planes when the wings are inactive, and a driving propeller for driving the car.

In testimony whereof, I do affix my signature in presence of two witnesses.

ADALBERT DOMARADSKI.
